CLAIM

The ornamental design for a pendant lamp as shown and described.

DESCRIPTION

FIG. 1 is a perspective view of the pendant lamp;
FIG. 2 is a front elevational view of the pendant lamp;
FIG. 3 is a rear elevational view of the pendant lamp;
FIG. 4 is a left side elevational view of the pendant lamp;
FIG. 5 is a right side elevational view of the pendant lamp;
FIG. 6 is a top plan view of the pendant lamp;
FIG. 7 is a bottom plan view of the pendant lamp; and,
FIG. 8 is a perspective view of the pendant lamp with a clear shade.

The broken line portions of the drawings are included to show portions of the pendant lamp that form no part of the claimed design.

The claimed design is shown with symbolic breaks. The appearance of any portion of the pendant lamp between the symbolic break lines forms no part of the claimed design.
